(57) **CLAIM**

The ornamental design for, a motor scooter or motor scooter replica, as shown and described.

DESCRIPTION

FIG. 1 is a front and left side perspective view of a motor scooter or motor scooter replica thereof, showing our new design;

FIG. 2 is a rear and right side perspective view thereof;

FIG. 3 is a front elevation view thereof;

FIG. 4 is a rear elevation view thereof;

FIG. 5 is a top plan view thereof;

FIG. 6 is a right side elevation view thereof; and,

FIG. 7 is a left side elevation view thereof.

The broken lines illustrate unclaimed portions of the motor scooter or motor scooter replica.
